Patented May 8, 1962

192,735

JIG LURE

Henry E. De Zeeuw, 8135 E. Broadway,
Lemon Grove, Calif.

Filed Sept. 2, 1958, Ser. No. 52,465

Term of patent 14 years

(Cl. D31—4)

Fig. 1

Fig. 2

I claim:

The ornamental design for a jig lure, as shown.
